UNITED STATES PATENT OFFICE

MAX VON RADICS AND RAYMOND LASKER, OF SPRINGFIELD, MASSACHUSETTS

FOUNTAIN SHAVING BRUSH

Application filed October 9, 1930. Serial No. 487,455.

Our invention relates to improvements in fountain shaving brushes.

An object of our invention is to provide within the handle of the shaving brush a storage member for the shaving cream, thereby adding greatly to convenience in shaving and also to convenience in traveling, as our combined brush and shaving cream container occupies only the space of one article, instead of two.

A further object is to provide means for introducing a charge of shaving cream into the approximate center of the bristles of the brush, thereby insuring an even distribution of the lather throughout the bristles.

Other objects and advantages of our invention will appear in the drawings, description and appended claims.

Broadly, our invention consists of a shaving brush comprising a tubular or hollow handle member, a brush removably secured to the handle, a storage cylinder for the cream that is removably secured within the tubular or hollow handle, a valve in the storage cylinder extending into the center of the brush, means for ejecting a charge of shaving cream through the valve into the brush, and a closure cap on the open or lower end of the storage cylinder with means therein for opening and closing the valve.

A preferred form of our invention is illustrated in the accompanying drawings, in which

Fig. 1 is a side elevational view of the complete brush, showing the valve operating and cap means for indicating the open and closed positions of the cream discharge valve, and hook means for removing the piston from the storage cylinder when the cylinder is to be refilled.

Fig. 2 is a longitudinal sectional view on line 2—2 of Fig. 1, showing the valve construction, the cream cylinder, actuating piston and cap.

Fig. 3 is an end view of the valve on line 3—3 of Fig. 2, showing the valve in a closed position.

Fig. 4 is a similar view showing the valve in an open position.

Fig. 5 is a perspective view of the closure

cap, showing the key which revolves the storage cylinder when the cap is turned and the pin which retains the cap in place on the tubular brush handle, and

Fig. 6 is a perspective view of the end of the brush handle and storage cylinder showing the key socket in the storage cylinder, the bayonet joint construction in the handle for retaining the cap in place, and indicating means for the open and closed positions of the valve.

Referring to the drawings in detail, in which like numerals refer to like parts throughout:

A collar member 1, in which is secured the cemented end 2 of the bristles of the brush 3, is frictionally secured in the recessed or socket end 4 of the tubular or hollow brush handle 5. The socket 4 is formed with an end wall 6, from which extends the cylindrical portion 7, having the closed end 8 which is formed with the opening 9, eccentrically disposed with relation to the center of the end 8. The cylindrical part 7 extends through the opening 10 in the cemented end 2 of the brush 3. The shaving cream storage member 11 slips into the tubular hollow handle 5 of the brush which is formed with the projecting, cylindrical end portion 12, in the closed end 13, of which is an opening 14 whose center is eccentrically located at the same distance from the common axis of the parts 7 and 12, as the opening 9.

The opposite end of the cream storage member 11 is open, and formed with a recess or keyway 15 cut in the edge 16, as shown. The plunger or piston 17 is formed with the push button 18. This plunger is frictionally and movably retained within the cream storage cylinder 11. The end 19 of the handle 5 is formed with the passageway or slot 20 which leads into the arc-shaped slot 21 that extends in opposite directions from the slot 20. A cap 22, knurled on the outside for convenience in turning, when grasped by the hand, is formed with the key or pin 23 and a central opening 24 in the end 25. A pin 26, in the cap 22, when the cap is assembled, engages in the arc-shaped slot 21, and serves the dual purpose of retaining the cap 22 in

place on the tubular member or brush handle 5 and acting as a stop for the open and closed positions of the valve 12. The open and closed positions of the valve and the location 5 of the pin 26 in the slot 21 are indicated on the handle 5 by appropriate letters or marks as "O" and "C", as shown at 27. An opening 28 in the push button 18 of the piston or plunger provides for the removal of the 10 plunger 17, when it becomes necessary to refill the cream storage cylinder 11 for this purpose, a wire hook 29 formed with a finger ring 30, is inserted in the opening 28, and the plunger is then pulled out of the cream cylinder 11.

In operation, when it is desired to inject a charge of shaving cream into the brush the cap or ring 22 is turned into the pin 26 has been moved from the closed or "C" position 20 to the open or "O" position. Since the cap is keyed to the storage cylinder by means of the key 23 entering the slot 15, it turns the cylinder when the cap is rotated until the valve openings 9 and 14 register. A slight 25 push on the bottom of the plunger forces a charge of cream through the openings 9 and 14 into the bristles of the brush. The cap is then turned back to closed or "C" position, turning the cylinder and returning the opening 30 14 to the position shown in Fig. 3, thereby closing the opening 9. When the cream has been exhausted, the cap 22 is removed by aligning the pin 26 with the slot 20. The 35 plunger 17 drawn out, by means of the hook 29, the cream cylinder 11 can then be refilled, and the plunger and cap replaced.

What we claim is:

1. In a fountain shaving brush, a tubular handle member, a storage casing member for 40 the shaving cream located within said handle member, and means for ejecting a charge of the shaving cream into the bristles of said brush, said means including registering valve openings in said cream storage casing member an in said handle member and extending through the butt end of the brush into the bristles.

2. A fountain shaving brush comprising a 55 tubular handle, a socket or recess portion at one end of said handle, a brush head removably secured in said socket, a cylindrical valve body formed as a part of the socket or recess of the handle and extending through a central opening in the butt end of the brush and having an opening eccentrically located in the end thereof, a cream storage casing member removably secured within the tubular handle and formed with an extended valve portion which fits within the said valve body and having an opening eccentrically located therein, means for turning said storage cream casing member for the purpose of registering the opening in the valve body with the opening in the valve, and means for ejecting a charge 65 of shaving cream from the storage casing

member through said openings into the bristles of the brush.

3. In a fountain shaving brush construction having a tubular handle with an open end, a shaving cream storage casing member 70 removably insertable within said handle, a valve communicating between said casing member and the central portions of the bristles of the brush, a pushable plunger in said casing for the purpose of expelling a 75 charge of shaving cream through said valve, a rotatable cap removably secured to the open end of the handle and keyed to the cream storage casing for the purpose of opening and closing said valve by turning said cap, and 80 means on said cap and said handle for indicating the position of said valve.

4. A fountain shaving brush comprising a 85 tubular handle having a socket portion, a brush head removably secured in the socket, a shaving cream container removably secured within the handle, a valve providing a 90 passage between said container and the bristles of said brush, a cap keyed to said container and removably secured to the handle for the purpose of opening and closing said valve, a push plunger in said container for the purpose of forcing a charge of shaving cream through 95 said valve, and means for removing said cap and said plunger for the purpose of refilling 100 said container.

5. A fountain shaving brush comprising in combination, a tubular handle, formed with an arc-shaped slot and a slot leading to the arc-shaped slot, the handle having a tubular 105 extension portion with an opening in its end, a removable cream containing member insertable within the tubular handle, the container member having a tubular extension which enters the tubular extension of the handle, and an eccentric opening in its end for registering 110 with the opening in the tubular extension of the handle, a brush head located on the first mentioned tubular extension, ring means connected to the cream container member for rotating the same to cause the openings to register, a cream expelling member, and means on the ring means located in the arc-shaped slot for removably retaining the ring means 115 on the tubular handle.

6. A fountain shaving brush comprising in combination, a tubular handle, formed with an arc-shaped slot and a slot leading to the arc-shaped slot, the handle having a tubular 120 extension portion with an opening in its end, a removable cream containing member insertable within the tubular handle, the container member having a tubular extension which enters the tubular extension of the handle, and an eccentric opening in its end for registering 125 with the opening in the tubular extension of the handle, a brush head located on the first mentioned tubular extension, ring means connected to the cream container member for rotating the same to cause the openings 130

to register, a cream expelling member, and
means on the ring means located in the arc-
shaped slot for removably retaining the
ring means on the tubular handle, said means
5 comprising a pin on the ring and a slot which
enters the arc-shaped slot.
